UNITED STATES PATENT OFFICE.

CLIFFORD G. RILEY, OF SALE, ENGLAND.

DRIVING WHEEL FOR CLOCKS.

Application filed January 21, 1922. Serial No. 530,960.

To all whom it may concern:

Be it known that I, CLIFFORD GARIEL RILEY, a British subject, residing at Sale, county of Chester, England, have invented 5 certain new and useful Improvements in Driving Wheels for Clocks, of which the following is a specification.

The invention relates to weight actuated driving mechanism for sustaining a weight 10 cord for clockwork mechanism by which the re-winding or raising of the weight can be readily effected after its descent.

It comprises a simple construction of cord wheel or pulley whereby a clock or other 15 similar instrument may be driven by a weight and cord and rewound without the use of ratchet mechanism.

It has the advantage of being extremely 20 simple and rigid and for this reason cannot get out of order. It has also the advantage of being easily manufactured and can therefore be produced at a small cost.

The invention will be fully described with 25 reference to the accompanying drawings.

Fig. 1 is a front elevation showing a modified construction of driving wheel and cord pulley or wheel stamped from one piece.

Fig. 2 is a sectional elevation of same.

According to the invention a cord pulley 30 A and a toothed driving wheel B are pressed or stamped from wheel metal in one piece as shown. Around the centre the part marked a^2 is pierced or stamped out leaving half the number of teeth a and the integral strips a' to form the corresponding number of teeth to form the cord pulley or wheel A. The teeth a are bent outward at their base to an angle of from 35° to 40° and the centre a^3 is dished out along the strips a' to form

40 the other side of the serrated or interrupted cord groove. The wheel B may be formed with an annular rib or corrugation b to stiffen it, and to prevent the cord catching in the teeth around its periphery.

45 A cord or string C is passed over the pulley A so as to lie in the serrated or interrupted groove formed by the bent teeth a

round its periphery, giving to the cord C a waviness of line as it passes over the periphery between the teeth.

A weight W is attached to one end of the cord or string C, and a weight W' to the other end the weight W being considerably heavier than the weight W', the tension thus produced on the cord will cause it 50 to lie between the teeth a and the gaps of the wheel in a wavy line, this waviness preventing the cord C from slipping. In order to re-wind, the heavier weight W is lifted, thus destroying the tension on that part of 55 the cord up to the wheel A. The cord which happens to lie on the wheel at the time therefore loses its wavy shape and will then slip over the wheel, past the teeth, being drawn by the smaller weight W'. The driving power developed during the descent of 60 the large weight W will be equal to the difference in weight between the two weights. The larger or heavier weight W is preferably about four times as heavy as the 65 other weight W'. The result is that the large weight W after descent may be raised so as to re-wind 70 the clock by the simple application to it of upward pressure.

The result is that the large weight W after descent may be raised so as to re-wind 75 the clock by the simple application to it of upward pressure.

What I claim as my invention and desire to protect by Letters Patent is:—

In a weight driven clockwork mechanism a compound driving wheel stamped from sheet metal comprising a dished centre 80 pierced out to form the teeth, half of the teeth being bent outwards at their base forming a serrated groove adapted to receive the weight cord and the periphery formed with pinion teeth adapted to mesh with the 85 clock train substantially as described.

In testimony whereof I have hereunto set my hand in presence of two subscribing witnesses.

C. G. RILEY.
